Primary Examiner — Bridget L Eland(74) *Attorney, Agent, or Firm* — Cantor Colburn LLP(57) **CLAIM**

The ornamental design for a portable radio two-way communications device, as shown and described.

DESCRIPTION

FIG. 1 is a perspective view of a portable radio two-way communications device;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof; and,

FIG. 8 is a front view showing environmental display characters and icons.

The broken lines immediately adjacent the shaded areas, and define unshaded regions, represent the bounds of the claimed design while all other broken lines are directed to environment and are for illustrative purposes only; the broken lines form no part of the claimed design.
